[57] **CLAIM**

The ornamental design for a myopic corrective insert for
refractive surgery, as shown and described.

DESCRIPTION

FIG. 1 is a perspective view of a myopic corrective insert for
refractive surgery;

FIG. 2 is a top view thereof;

FIG. 3 is a side view thereof;

FIG. 4 is a bottom view thereof;

FIG. 5 is a cross-sectional view taken along lines 5—5 of
FIG. 2; and,

FIG. 6 is a perspective view of a myopic corrective insert for
refractive surgery without scale markings on the top surface
thereof.

The bottom plan view, side elevational view and cross-
sectional view of the embodiment of FIG. 6 are identical to
the embodiment of FIG. 1.
